UNITED STATES PATENT OFFICE.

CHARLES C. DRUEDING, OF PHILADELPHIA, PENNSYLVANIA, ASSIGNOR TO DRUEDING BROTHERS COMPANY, OF PHILADELPHIA, PENNSYLVANIA.

POLISHING GLOVE.

Application filed January 18, 1923. Serial No. 613,518.

To all whom it may concern:

Be it known that I, CHARLES C. DRUEDING, a citizen of Philadelphia, in the county of Philadelphia and State of Pennsylvania, have invented new and useful Improvements in Polishing Gloves, of which the following is a specification.

The invention relates to a reversible chamois polishing glove.

10 The object of the present invention is to provide a simple, practical and efficient reversible chamois polishing glove of strong, durable and comparatively inexpensive construction designed for polishing automobiles, furniture and various other highly polished surfaces of either wood or metal or other material.

20 A further object of the invention is to provide a chamois polishing glove of this character adapted to be turned or rotated transversely on the hand to present at the palm thereof either one of two complete polishing areas.

25 Another object of the invention is to provide a reversible chamois polishing glove of this character adapted to utilize at both the palm portion and the marginal edges small pieces of chamois arranged to present continuous polishing strips or portions to the 30 surface operated on.

35 A still further object of the invention is to provide a polishing glove comprising palm and back sections which are united at their marginal side and outer end edges, with one of the sections provided with rows 40 of polishing strips secured thereto and with each row of strips being composed of relatively short pieces having their ends arranged in overlapping relation so as to provide practically continuous strips, the 45 said pieces being united to the glove by a row or rows of stitching.

With these and other objects in view the invention consists in the construction and 45 novel combination and arrangement of parts hereinafter fully described, illustrated in the accompanying drawings and pointed out in the claims hereto appended, it being understood that various changes in the form, proportion and minor details of construction, 50 within the scope of the claims, may be resorted to without departing from the spirit

or sacrificing any of the advantages of the invention.

In the drawings, in which like characters 55 of reference designate corresponding parts in the several views:—

Figure 1 is a plan view of a reversible chamois polishing glove constructed in accordance with this invention. 60

Figure 2 is a longitudinal sectional view of the same.

Figure 3 is a transverse sectional view of the reversible chamois polishing glove.

Figure 4 is a detail sectional view on the 65 line 4—4 of Figure 3.

In the accompanying drawing, in which is illustrated the preferred embodiment of the invention, the reversible polishing glove, which is designed to be constructed of 70 chamois, may, of course, be made of any other suitable material and it comprises in its construction two similar sections or members 1, consisting of sheets or pieces of chamois stitched together at their marginal 75 side and outer end edges, as indicated at 2, and provided at their inner ends with gauntlet extensions 3, preferably tapered as shown and adapted to cover the wrist of the person using the reversible polishing glove. The 80 sheets or members 1, which constitute back and palm sections of the glove, are rounded at their outer end edges and converge inwardly or rearwardly slightly at the inner half of the polishing glove, as clearly illustrated in Figure 1 of the drawings. This 85 enables the polishing glove to comfortably receive and substantially fit the hand of the user when the fingers are spread and it provides a contracted wrist portion and an enlarged outer portion, which will effectually prevent the reversible polishing glove from accidentally slipping off of the hand when in use. The gauntlet extensions of the palm 90 and back sections of the reversible polishing glove are preferably provided at the marginal edges with rows of stitching 4 for protecting and ornamenting the gauntlet extensions, which may also be further ornamented by rows of stitching 5 extending 100 across the gauntlet extensions in the general direction of the length of the reversible polishing glove.

The reversible polishing glove is provided

at both the palm and back sections with a plurality of rows of longitudinal polishing strips 6 of chamois, each row consisting of a plurality of relatively short pieces secured 5 to the sections 1, preferably by parallel rows of longitudinal stitching 7 spaced apart and located at opposite sides of the center of the row. The short pieces, which may be arranged in one or more thicknesses in each 10 of the longitudinal rows, have their ends 8 arranged in overlapping relation to eliminate openings or space between the adjacent ends of the contiguous short strips to provide practically a continuous unbroken strip 15 extending from the gauntlet portion 3 to the outer ends of the palm and back sections. This will enable the practically continuous longitudinal polishing strips to be made of short or small pieces and at the same time 20 present practically unbroken sides or wings throughout the entire length of each of the rows.

The reversible polishing glove is also provided at the top marginal edges with projecting marginal polishing loops 9 consisting of 25 short pieces doubled to provide a loop formation and secured at the ends to the palm and back sections of the reversible glove by the marginal rows of stitching and disposed substantially at right angles to the said marginal 30 rows of stitching. The marginal polishing loops are arranged in overlapping relation, as clearly illustrated in Figure 4 of the drawings, so that the side edges of each of the marginal polishing loops, with the exception of 35 the loops, are overlapped by adjacent polishing loops. This provides an efficient polishing edge and enables the reversible polishing glove to be used in edgewise polishing relation 40 without liability of subjecting the polishing glove to excessive wear and at the same time enabling the polishing glove to effectively operate in corners, grooves and other narrow places. The marginal polishing loop 45 protects the stitched marginal edges of the back and palm sections by reinforcing and binding the same and provides a plurality of thicknesses at the marginal edges of the glove for the said edgewise polishing action of the 50 glove.

The interior space within the polishing glove, defined by the marginal stitching of the attached edges of the palm and back sections is entirely open for the accommodation 55 of the hand and the polishing glove may be reversed by simply rotating it on the hand of the user without removing the hand from the glove.

What is claimed is:—

60 1. A reversible polishing glove comprising palm and back sections united at their marginal side and outer end edges, and rows of polishing strips secured to the palm and back section, each row composed of a plurality 65 of relatively short pieces having their

contiguous ends arranged in positive overlapping relation to form substantially continuous strips, said pieces being united to the said sections by spaced longitudinal rows of stitching. 70

2. A reversible polishing glove comprising palm and back sections united at their marginal side and outer end edges, and marginal polishing strips secured to the reversible polishing glove on both sides of the marginal edges 75 thereof to reinforce the edges of the glove and extending outwardly from the same to provide marginal polishing portions adapted to permit the glove to be used for edgewise polishing. 80

3. A reversible polishing glove comprising palm and back sections united at their marginal side and outer end edges, and marginal polishing strips of loop formation secured to the glove on both sides of the marginal edges 85 thereof to reinforce the edges of the glove and to provide marginal strips of double thickness projecting therefrom substantially at right angles thereto.

4. A reversible polishing glove comprising 90 palm and back sections united at their marginal side and outer end edges, and marginal polishing strips arranged in loop formation and secured to the marginal edges of the said sections and projecting therefrom substantially 95 at right angles, said loops being arranged in overlapping relation at their side edges.

5. A reversible polishing glove comprising 100 palm and back sections united at their marginal side and outer end edges, rows of polishing strips secured to the palm and back section, each row composed of a plurality of 105 relatively short pieces having their contiguous ends arranged in overlapping relation, said pieces being united to said sections by spaced longitudinal rows of stitching, and marginal polishing strips arranged in loop formation and secured to the marginal edges of said sections and projecting therefrom 110 substantially at right angles, said loops being arranged in overlapping relation at their side edges. 110

6. A reversible polishing glove comprising 115 palm and back sections united at their marginal side and outer end edges, rows of polishing strips secured to the palm and back sections, each row composed of a plurality of relatively short pieces, and marginal polishing strips arranged in loop formation 120 and secured to the marginal edges of the said sections and projecting therefrom substantially at right angles, said loops having their terminal portions fitted against the exterior of the palm and back sections and forming 125 a protecting binding for the same, and the adjacent side edges of the marginal loops being arranged in overlapping relation.

7. A polishing glove comprising palm and back sections united at their marginal side 130

and outer end edges, and rows of polishing strips secured to the palm section, each row composed of a plurality of relatively short flexible pieces arranged longitudinally of the glove and having their contiguous ends arranged in overlapping relation to form substantially continuous strips.

8. A polishing glove comprising palm and back sections united at their marginal side and outer end edges, and rows of polishing

strips secured to the palm section, each row composed of a plurality of relatively short flexible pieces having their contiguous ends arranged in overlapping relation to form substantially continuous strips, said pieces 15 being united to the palm section by spaced longitudinal rows of stitching.

In testimony whereof I have hereunto set my hand.

CHARLES C. DRUEDING.
